CLAIM

The ornamental design for a tackle stowage device, as shown and described.

DESCRIPTION

FIG. 1 is a perspective of the tackle stowage device of the instant invention in an open position wherein the broken line showings of the various items placed therein are for illustrative purposes only and form no part of the claimed design; FIG. 2 is a perspective of the tackle stowage device of the instant invention in an open position;

FIG. 3 is a front elevational view thereof;

FIG. 4 is a right side view thereof;

FIG. 5 is a left side view thereof;

FIG. 6 is a plan view thereof;

FIG. 7 is a bottom plan view thereof; and,

FIG. 8 is a back view thereof.
